UNITED STATES PATENT OFFICE.

JOSEPH P. BROWNE, OF PRINCETON, INDIANA.

CARPET-STRETCHER.

SPECIFICATION forming part of Letters Patent No. 437,971, dated October 7, 1890.

Application filed April 24, 1890. Serial No. 349,375. (No model.)

To all whom it may concern:

Be it known that I, JOSEPH P. BROWNE, a citizen of the United States, residing at Princeton, in the county of Gibson and State of Indiana, have invented certain new and useful 5 Improvements in Carpet-Stretchers, of which the following is a specification, reference being had therein to the accompanying drawings, in which—

10 Figure 1 represents a perspective view of my improved stretcher in position for operation; Fig. 2, a similar view of the stretcher folded up for transportation or packing away; Fig. 3, a detail perspective view of the hinge- 15 connection between the sections of the main bar.

The object of the invention is to provide an extremely simple device for stretching carpets and holding them in a stretched condition 20 until tacked to the floor, the said device being very strong and practical and capable of folding up for packing or transportation purposes; and it consists in certain novel features of construction and combination of 25 parts, that will be fully hereinafter set forth.

Referring to the drawings by letter, *a* designates the main bar, having secured to its forward end a cross-bar *b*, provided with teeth on its under side to engage the carpet. This 30 main bar is pivotally clamped by a horizontal bolt *c* between the forward ends of a pair of bars *d*, which have a block *e* interposed and secured between their rear ends to keep them separated. The main bar *a* may be provided 35 with additional apertures along its length for the passage of the bolt *c*, in order that the same may be adjusted.

In operation the rear end of the main lever is raised and the teeth of the cross-head inserted in the carpet near the wash-board. The 40 operator then places his foot upon the rear end of the frame *d d* to prevent its moving, and bears down upon the rear elevated end of the main lever, whereupon the cross-head 45 forces the carpet toward the wash-board and holds it in such stretched condition until secured to the floor.

The parts of the device may be of any suitable dimensions. For instance, they may be

made long enough to extend from one side of the room to the other.

The rear end of the frame *d d* may be provided with teeth or spikes, if desired, in order to enter the floor and prevent the frame moving during operation, and thereby render it unnecessary for the operator to place his foot thereon for that purpose.

In order that the apparatus may be folded up, as shown in Fig. 2, the main bar *a* may be constructed of two sections and hinged together by a hinge *f* just forward of the pivotal bolt *c*, the said hinge being secured upon the upper side of the bar, as shown.

To secure the two sections of the main bar together and make them rigid while in operation, I pivotally secure on the under side of one section of the bar (preferably the rear section) a swinging plate *g*, provided with a longitudinal slot, and on the under side of the adjacent section a flat thumb-screw *h*, capable of passing through the slot in the plate *g*.

To make the sections rigid, it is simply necessary to place the swinging plate over the thumb-screw, and then give the latter a quarter-turn to bring it at right angles to the slot 75 in the plate.

Having thus fully described my invention, what I claim is—

In a carpet-stretcher, the combination of a frame composed of the parallel bars *d d*, a bar *a*, pivotally secured between the forward ends of the bars *d d* and provided with a toothed cross-head at its forward end, the said bar *a* being composed of two abutting sections hinged together on their upper sides 85 forward of the pivotal connection to the bars *d d*, a slotted plate *g*, hinged to the under side of one of the sections of the bars *a* and adapted to lap over upon the adjacent section, and a flat set-screw *h*, passed through 90 the slot in this plate and screwed into the adjacent section, substantially as described.

In testimony whereof I affix my signature in presence of two witnesses.

JOSEPH P. BROWNE.
